UNITED STATES PATENT OFFICE.

ERIC GAYTER, OF ALTRINCHAM, ENGLAND, ASSIGNOR TO LINOTYPE AND MACHINERY LIMITED, OF LONDON, ENGLAND, A BRITISH COMPANY.

TYPOGRAPHICAL LINE COMPOSING AND CASTING MACHINE.

Application filed May 26, 1925, Serial No. 32,890, and in Great Britain June 12, 1924.

This invention relates to typographical line composing and casting machines, such as those known commercially under the trade mark "Linotype" and kindred machines which produce cast lines of type or slugs. More particularly it relates to those machines wherein, during the casting operation, the composed line of matrices is supported in a vise frame between two vise jaws of which the left-hand one is operatively engaged with a wedge block located outside of the vise cap and there engaging with a movable wedge which serves to move the said left-hand vise jaw towards the right-hand one for effecting what is known as the second justification.

In a machine of this particular construction there has heretofore been provided a serrated bar or rack engaged by the left-hand vise jaw and projecting to a very considerable extent beyond the left-hand end of the vise cap. This bar or rack has consequently been very liable to damage by operators passing to and fro at that side of the machine.

The object of the present invention is so to construct the vise mechanism as to overcome the aforesaid difficulty, this being attained by locating the rack within the head of the vise itself and thereby avoiding the necessity for having any vital or delicate parts overhanging the left-hand end of the vise cap.

The invention will now be described by reference to the accompanying drawings in which Figures 1, 2 and 3 are representative of one constructional form and Figure 4 is representative of a modification thereof, the first three figures being respectively a front elevation, a left-hand side elevation, and a plan, while Figure 4 is also a front elevation.

In the constructional form shown in Figures 1, 2 and 3, the rack 1 is at one end slidably secured, as by a slot-and-screw connection 2, to the head 3 of the vise frame 4, and at the other end it is attached, by screws 5, to the wedge block 6. With this wedge block, the vertically movable wedge 7 operates in the well-known manner to move the left-hand vise jaw 8 rightward for effecting the second justification.

The vise jaw 8 is normally engaged with the rack 1 through a detent 9 which is vertically slidable in a recess in the so-called

vise-jaw casting 10, which recess also houses a spring 11 which always tends to hold the detent 9 in engagement with the rack 1. The detent 9 is pivoted to the horizontal arm of a bell-crank lever 12 which, by a screw or pin 13, is pivoted to the vise-jaw casting 10 and whose upstanding arm, through a screw-threaded extension 14, pivotally or loosely engages with an enlarged hole or slot in the known releasing rod 15, as shown in Fig. 3.

The lever extension 14 penetrates a narrow slot 16 (shown in dotted lines in Figure 3) formed in the cap or top of the vise head 3, this slot being of such length as will allow the vise-jaw 8 its full range of motion.

The releasing rod 15, as ordinarily, is longitudinally slidable in a groove 3^a in the top of the vise head 3, and provided at its right-hand end with an upstanding thumb-piece 17 by which it can be moved rightward in opposition to the spring 11, for effecting the disengagement of the detent 9 from the rack 1, prior to the adjustment in the well-known manner, by means of the upstanding plate 18, of the vise-jaw 8, this plate, as ordinarily, being attached by its sliding rod 19 and a vertical pin 20 to the vise-jaw casting 10. The sliding rod 19 underlies the releasing rod 15, and both of said rods are retained in sliding connection with the vise head, by a plate 21 screwed to the latter.

When, with the foregoing arrangement, it is desired to adjust the vise-jaw 8 to a new position, the operator grasps the two members 17, 18, so as to move the former towards the latter and thereby disengage the detent 9 from the rack 1 and then moves these members to bring the jaw to the desired position, which latter can be decided by reference to a scale 22, Figure 3, the subsequent release of the members 17, 18, permitting the detent to again engage with the rack under the influence of the spring 11, and thereby lock the jaw in the position thus arrived at.

As it is sometimes required to bring the left-hand vise-jaw 8 into contact with the right-hand vise-jaw 23, as when blank slugs are to be cast, and the jaw 8 must be reset in its original position after each such operation, the foregoing construction calls for the accurate determination of such position

by means of the scale 22 which may involve some slight delay. This delay, however, can be entirely avoided by adopting the construction shown in Figure 4, in which the 5 detent 9 and lever 12 are mounted in a block 24 formed independently of the vise-jaw casting 10, and the rod 19 is attached to this block, instead of, as in the before described example, to the casting 10 itself. In this 10 arrangement therefore, the vise-jaw 8 which abuts block 24 can be moved into position for casting blank slugs without disturbing the setting of the block 24, and after such casting the said jaw can be moved outwardly 15 into contact with the block which accurately determines its position without reference to any scale.

It is preferred to provide a stop 25 which can be adjusted to, and clamped in, any desired position along the groove 3^a, and this serves to prevent any unintentional outward deflection of the block 24, when the jaw 8 contacts with it.

Having described my invention, I declare 25 that what I claim and desire to secure by Letters Patent is:—

1. In a typographical line composing and slug casting machine, the combination of a 30 vise frame, a vise jaw supported in the head of that frame, a guide in said head wherein the jaw is movable, a locking detent for the said jaw located within said head, a rack bar the toothed portion of which is engaged by the detent and located wholly within the 35 head, and a wedge block fast to the rack bar and located externally of the vise head.

2. In a typographical line composing and slug casting machine, the combination of a 40 vise frame, a vise jaw supported in the head of that frame, a guide in said head wherein the jaw is movable, an actuating body for the movable vise jaw, a locking detent for the jaw movable within that body, a rack bar the toothed portion of which is engaged by the 45 detent and located wholly within the head, and a wedge block fast to the rack bar and located externally of the vise head.

3. In a typographical line composing and slug-casting machine, the combination of a 50 vise frame, a vise jaw supported in the head of that frame, a guide in said head wherein the jaw is movable, a body movable independently of and operatively engaged by the vise jaw, a locking detent for the jaw 55 movable within that body, a rack bar the toothed portion of which is engaged by the detent and located wholly within the head, and a wedge block fast to the rack bar and located externally of the vise head.

4. In a typographical line composing and 60 slug casting machine, the combination of a vise frame, a vise jaw supported in the head of that frame, a guide in said head wherein the jaw is movable, an actuating body for the 65 movable vise jaw, a locking detent for the

jaw movable within that body, a rack bar the toothed portion of which is engaged by the detent and located wholly within the head, a spring interposed between the body and the detent to press the latter into engagement with the rack, a manually-controlled detent-releasing lever pivoted to the body, and a wedge block fast to the rack bar and located externally of the vise head. 70

5. In a typographical line composing and slug casting machine, the combination of a 75 vise frame, a vise jaw supported in the head of that frame, a guide in said head wherein the jaw is movable, a body movable independently of and operatively engaged by the vise jaw, a locking detent for the jaw 80 movable within that body, a rack bar the toothed portion of which is engaged by the detent and located wholly within the head, a spring interposed between the body and the 85 detent to press the latter into engagement with the rack, a manually-controlled detent-releasing lever pivoted to the body, and a wedge block fast to the rack bar and located externally of the vise head. 90

6. In a typographical line composing and slug casting machine, the combination of a 95 vise frame, a vise jaw supported in the head of that frame, a guide in said head wherein the jaw is movable, a body movable independently of and operatively engaged by the vise jaw, a stop adjustably secured to the vise frame adapted to arrest the body in different 100 positions, a locking detent for the jaw movable within that body, a rack bar the toothed portion of which is engaged by the detent and located wholly within the head, and a wedge block fast to the rack bar and located externally of the vise head. 105

7. In a typographical line composing and slug casting machine, the combination with 110 a vise frame, two vise jaws supported by said frame, and a guide in the vise frame wherein one of the vise jaws is movable towards and away from the other one, of an actuating body for the movable vise jaw, a detent operatively connected to the body, a toothed rack engaged by the detent and slideable within the head of the vise frame, and of which only one end projects to the outside 115 of the said head, a block fast to this projecting end and means exterior of the vise head co-operating with said block to move one jaw towards the other. 120

8. In a typographical line composing and slug casting machine, the combination with 125 a vise frame, two vise jaws supported by said frame, and a guide in the vise frame wherein one of the vise jaws is movable towards and away from the other one, of an actuating body for the movable jaw, a detent vertically adjustable in said body, a toothed rack engaged by the detent and slideable within the head of the vise frame, and of which only one end projects to the outside of the said 130

head, a spring normally holding the detent in engagement with the rack, manual means disengaging the detent from the rack, a block fast to the outwardly projecting end of the rack, and means exterior of the vise head co-operating with said block to decrease the distance between the vise jaws.

9. In a typographical line composing and slug casting machine, the combination with a vise frame, two vise jaws supported by said frame, and a guide in the vise frame wherein one of the vise jaws is movable towards and away from the other one, of a vise jaw casting fast to the movable jaw, a body independent of the vise jaw casting but slidable in the head of the vise along with and inde-

pendently of the movable jaw, a detent vertically movable in said body, a toothed rack engaged by the detent and slidable within the head of the vise frame, and of which only one end projects to the outside of the said head, a spring normally holding the detent in engagement with the rack, manual means disengaging the detent from the rack, a block fast to the outwardly projecting end of the rack, and means exterior of the vise head co-operating with said block to decrease the distance between the vise jaws.

In testimony whereof I have affixed my signature hereto.

ERIC GAYTER.
